INTERCHANGEABLE LAMP BRACKET

Filed June 9, 1927

UNITED STATES PATENT OFFICE.

ALFRED A. SMITH, OF NEW YORK, N. Y.

INTERCHANGEABLE LAMP BRACKET.

Application filed June 9, 1927. Serial No. 197,529.

This invention relates to lamp fixtures and more particularly to a construction whereby certain parts of the fixture may be interchanged and quickly adjusted and assembled in different positions.

A further object of my invention includes a construction of electric light supports and outlet box cover plates which are simple in construction, neat in appearance, substantial and serviceable in use and wherein the cover plate is easily shifted and fastened in varying positions as conditions and positions of the outlet box may require.

Other objects will appear hereinafter and I obtain these objects by the constructions illustrated in the accompanying drawings in which,

Fig. 1 is a view in elevation of a construction having my invention applied thereto.

Fig. 2 is a view taken on the line 2—2 of Fig. 1 with the cover plate in vertical position as shown by the dotted lines.

Figs. 3 and 4 are views of a portion of said lamp brackets and showing the supporting lugs, and

Fig. 5 is a portion of the outlet box cover plate.

Like reference numerals refer to the same parts throughout the several views.

It is a prime purpose of my invention to produce an electric light fixture which can be quickly assembled or applied in varying positions. To this end I provide a cover plate 10 of neat and attractive design and large enough to cover the outlet box 11 which may be set in the wall or door frame 12, either vertically or horizontally. The cover plate is provided with an outer border skirt 13 and a centrally disposed dome 14 which is provided with an angular opening 15. In the illustrative construction I have shown the opening 15 to be rectangular, but other angular openings may be used without departing from the spirit and scope of my invention.

I also provide a bracket holding plate or bar 16 which is fastened on the outlet box 11, by screws 17. In the center of said plate or bar, I provide an anchor rod 18, which is preferably screw-threaded to engage the bar 16, and is locked by a lock-nut 19. The free end of the screw rod 18 extends through the opening 15 to engage the light bracket 20. This bracket is provided with lugs 21 which fit into the angular opening 15 to engage the dome part of the plate in varying positions. In the rectangular construction shown the plate may be applied horizontally as shown in full lines in Fig. 1, or it may be held vertically as shown in Fig. 2, or by the dotted lines of Fig. 1. This provision is a great advantage for quickly and inexpensively installing light fixtures. A nut 22 holds the parts assembled as shown and a double armed bracket is shown as a preferred form. Obviously, however, different types of arms may be used in connection with my invention without departing from the scope and spirit thereof.

What I claim therefore, as new and useful and desire to secure by Letters Patent is:

A light fixture and cover plate for covering outlet boxes in vertical or horizontal positions, a cover plate having a skirt and dome with a rectangular opening therein, an anchor bar on said outlet box, a screw threaded rod extending from said bar through the opening in said dome, a light bracket having a bore to receive said screw-threaded rod, lugs in said bracket to engage the angular opening in said dome in a position to hold the cover-plate firmly over the outlet box in either horizontal or vertical positions and means for securing the cover plate and bracket in said fixed relation.

ALFRED A. SMITH.
